UNITED STATES PATENT OFFICE

ERROL W. GOFF, OF EVERETT, MASSACHUSETTS, ASSIGNOR TO WARREN TELECHRON
COMPANY, A CORPORATION OF MAINE

DESIGN FOR A CLOCK OR THE LIKE

Application filed July 15, 1930. Serial No. 36,355. Term of patent 14 years.

To all whom it may concern:

Be it known that I, ERROL W. GOFF, a citizen of the United States, residing at Everett, in the county of Middlesex, State of Massachusetts, have invented a new, original, and ornamental Design for a Clock or the like, of which the following is a specification, reference being had to the accompanying drawing, forming a part thereof. The drawing is a front perspective view of a clock showing my new design.

I claim:

The ornamental design for a clock or the like as shown.

In witness whereof I have hereunto set my hand this tenth day of July, 1930.

ERROL W. GOFF.
